UNITED STATES PATENT OFFICE.

CHARLES HENRY REEVES, OF LA FAYETTE, INDIANA.

FIRE-GUARD.

No. 878,563.

Specification of Letters Patent.

Patented Feb. 11, 1908.

Application filed March 30, 1907. Serial No. 365,539.

To all whom it may concern:

Be it known that I, CHARLES HENRY REEVES, a citizen of the United States, residing at La Fayette, in the county of Tippecanoe 5 and State of Indiana, have invented certain new and useful Improvements in Fire-Guards, of which the following is a specification.

This invention is a guard for open fire places or grates, and has for its object to 10 provide an improved device of this kind so constructed that there will be no danger of the clothing of children or others taking fire, and also preventing ashes and cinders dropping on the floor.

15 A further object is to provide a guard which can be adjusted to fit fire places of different heights, and which can be readily opened and closed in order that access may be had to the fire for replenishing it. The 20 guard is also constructed so as not to shut off the heat from the room.

In the accompanying drawing, Figure 1 is a front elevation of the invention partly 25 in section. Fig. 2 is a horizontal section on the line 2—2 of Fig. 1. Fig. 3 is a vertical section on the line 3—3 of Fig. 1.

The invention comprises a pair of standards to which are hinged doors which close 30 in front of the fire place or grate. Each 35 standard comprises a tube 1 which seats at its lower end in a nut 2 carried by a base or foot 3 having a threaded stem 4. The nut screws on the threaded stem and has a socket 5 to receive the tube 1. On the outside of 40 the nut are spanner holes 6. In the bottom of the base is a rubber block 7 to prevent marring of the floor and slipping. The top 45 of the tube 1 is fitted with a rubber tip 8. In use, the standards will be placed under the mantel 9 or under any horizontal projection on the wall or mantel, with the base 3 on the floor. The nut 2 is then turned until the tip 8 bears tightly against the bottom of the mantel. The tip 8 and the block 7 prevent slipping, and the standards will be 50 securely held in position between the mantel and the floor. The nut 2 enables the standards to be readily adjusted to fit under mantels of different heights.

The doors comprise top and bottom bars 50 10 and 11, respectively, which are connected by vertical strips 12. On the tube 1 are mounted ball hinges 13 and 14, respectively, the latter being held in place by a collar 15 which is adjustably secured on the tube by 55 a set-screw 16 so that the doors may be adjusted up or down on the standards. The ball hinge 13 has a horizontally presented threaded stem 17, and the inner end of the bar 10 has a threaded socket into which the 60 stem screws whereby the bar and the hinge are connected. The bar 11 is connected to the hinge 14 in the same manner.

For holding the doors closed, they are provided with a suitable latch 18 which is carried by the top bar of one of the doors and is engageable with the top bar of the other door. To the bottom bars is secured a wire 65 netting 19 which extends down to the floor to prevent cinders, ashes, etc. being thrown 70 on the floor.

A guard constructed as herein described effectively serves the purpose for which it is intended, and can be readily put up and taken down without marring the mantel or 75 the floor. It does not shut off the heat of the fire from the room, and when the fire needs attention it can be readily reached by swinging the doors open.

I claim:—

1. A fire-guard comprising a base having a 80 threaded stem, a standard, a nut screwed on the stem and having a socket in which the standard seats, and doors hinged to the standard.

2. A fire-guard comprising a standard, means for supporting the standard adjacent a fire place, hinges on the standard having horizontally presented threaded stems, and doors having top and bottom bars provided 85 with threaded sockets in their inner ends into which the aforesaid stems screw.

In testimony whereof I affix my signature, in presence of two witnesses.

CHARLES HENRY REEVES.
